UNITED STATES PATENT OFFICE.

THOMAS C. BOOTH AND HELEN EMBURY, OF NEW YORK, N. Y.

SCREEN-HOLDER FOR LAMPS.

SPECIFICATION forming part of Letters Patent No. 351,157, dated October 19, 1886.

Application filed April 22, 1886. Serial No. 199,823. (No model.)

To all whom it may concern:

Be it known that we, THOMAS C. BOOTH and HELEN EMBURY, citizens of the United States, residing at New York, in the county 5 and State of New York, have invented new and useful Improvements in Screen-Holders for Lamps, of which the following is a specification.

This invention relates to a device for attaching a screen to the globe or chimney of a lamp; and it consists in certain novel features of construction, which are fully pointed out in the following specification and claims, and illustrated in the accompanying drawings, in 15 which—

Figure 1 shows our device secured to a lamp. Fig. 2 is a section of our device on the line xx , Fig. 3, drawn on a larger scale. Fig. 3 is a view of our device from the side that comes 20 toward the lamp when in use.

Similar letters indicate corresponding parts.

In the drawings, the letter A designates the screen, which, in the example shown in the drawings, is attached by means of rings a to a horizontal suspension-bar, B. This bar is secured to the attaching device C, which is 25 formed of one piece of material bent at its center so as to form the hook b, which passes over the upper edge of the globe or chimney D.

From this hook extend two divergent arms, $c c$, which are bent downward at d , so as to form the legs $e e$, from the lower edge of which extend the two braces $f f$, which rest against the globe or chimney of the lamp, and, to-

gether with the hook b , serve to hold the attaching device in position. It is obvious, however, that, if desired, the braces $f f$ may be dispensed with, and the legs $e e$ may rest against the globe or chimney directly.

What we claim as new, and desire to secure 40 by Letters Patent, is—

1. A screen-holder for lamps, consisting of a single piece of material formed integral with the central hook, b , the divergent lateral arms $c c$, and the legs $e e$, and the horizontal bar B, 45 connected to the divergent arms, and from which the screen is suspended, substantially as described.

2. A screen-holder for lamps, consisting of a single piece of material formed integral with the central hook, b , divergent arms $c c$, legs $e e$, and braces $f f$, and the horizontal bar B, 50 connected with the arms, and from which the screen is suspended, substantially as described.

3. The combination of the single piece of 55 material, formed with the central hook, b , divergent arms $c c$, and legs $e e$, with the horizontal bar B, connected with the arms, and the screen A, having rings a , suspending it from the bar, substantially as described. 60

In testimony whereof we have hereunto set our hands and seals in the presence of two subscribing witnesses.

THOMAS C. BOOTH. [L. S.]
HELEN EMBURY. [L. S.]
